UNITED STATES PATENT OFFICE.

GEORGE B. HAKINS, OF NORWOOD, NEW YORK.

DENTAL TOOL.

Application filed December 20, 1927. Serial No. 241,426.

This invention relates to a new and improved dental tool, designed to facilitate the transfer of filling material, such as amalgam, cement or the like, in desirable quantities, to the mouth of the patient, and its ready insertion in tooth cavities.

Tools, now in general use, intended to accomplish the above stated object, are objectionable, in being so constructed as to permit small adhering particles of the filling material to rapidly accumulate therein and harden until the tool becomes completely choked up, requiring it to be drilled out, in order to free the moving parts for effective operation.

A further objection to such tools, is the difficulty experienced in maintaining the tool in proper position over the tooth cavity, while actuating the plunger member thereof to eject the filling material. This separate operation of the plunger, which is ordinarily effected by pressure of the first finger of the hand holding the tool, frequently results in shifting the tool, more or less, and discharging the filling material at some distance from, instead of in the cavity. To recover such material and pack it in the tooth cavity involves careful and rapid work on the part of the dentist and unless successfully accomplished, is annoying to the patient.

In order to obviate the above mentioned and other objections to present day tools of the class mentioned, I have devised an improved construction in which the receptacle of the tool for holding the filling material, is formed in sections, normally spring-separated and designed to be brought together, for taking up the material, by pressure of the thumb and fingers of the hand of the operator, after the manner of manipulating a pair of tweezers. In providing normally spring-separated sections, the receptacle for filling material may be easily and readily cleaned so as to prevent any accumulation of adhering particles and the resulting choking up of the tool, as is common in present day tools.

I furthermore provide for the ejection of the filling material from the tool, and its insertion in the tooth cavity by a slight downward pressure of the tool, which may be effected without changing the grip or the position of the hand as the tool is grasped to fill the receptacle. The advantages will be apparent, as there will be

no tendency of the tool to shift and deposit the material outside of the cavity and the receptacle end of the tool will be in full sight and not obstructed by the finger of the operator, as is the case with present day tools.

In addition to the foregoing, various other meritorious features are embodied in the construction illustrated in the accompanying drawings, in which I have shown the preferred form of my invention.

In the drawings:

Fig. 1 is a perspective view of the tool;
Fig. 2 is a side elevation;

Fig. 3 is a similar view showing the position of the tool when under pressure, to eject the filling material from the containing receptacle.

Fig. 4 is a top plan view of the tool as in Figs. 1 and 2, and

Fig. 5 shows a slight modification.

Referring to the drawings, the body of the tool follows the general design of an ordinary pair of tweezers, in having two normally separated spring fingers 1, 1, secured together at their rear ends to form a shank or handle.

At the outer ends, each of the fingers carries a half section 2 of a cylindrical open ended receptacle, designed to take up and hold a small pellet of filling material for transfer to the cavity of the tooth to be filled.

In filling the receptacle, the half sections thereof may be closed upon the material, tweezer fashion, or they may be first brought together and then pressed down on the material, causing it to enter and fill the receptacle.

Formed as an extension of one of the fingers, there is a rigid member 3, which terminates at its outer end in a fixed plunger 4. As arranged, the plunger closes the upper end of the receptacle when the sections of the latter are pressed together to complete it and acts to eject the contained material therefrom in a manner now to be described.

As previously pointed out, it is important, once the tool is placed in position with its receptacle containing the filling material directly over the tooth cavity, to thus maintain it until the material is ejected from the receptacle and enters the cavity.

To enable this to be accomplished with the least possible disturbance of the tool, the fingers are reduced at a point intermediate their ends to provide spring sections 5, 5, the arrangement being such that slight down

pressure on the tool, in the hand of the operator, causes the spring sections 5, 5, to yield and the plunger to move downward in the receptacle, ejecting the filling material and 5 forcing it into the tooth cavity immediately below.

As will be evident, the required downward pressure may be applied without releasing the grip on the tool or changing the position 10 of the hand, so there is no tendency of the tool to move or shift out of line with the tooth cavity and consequently no accidental discharge of filling material outside of the cavity.

15 To insure proper alignment or registry of the receptacle sections as they are brought together, a guide pin 6, coacting with an opening 7, may be employed or one of the receptacle sections may be provided with a 20 projection 6^a, coacting with a notch 7^a in the other section.

The important advantages of the invention will be apparent from the foregoing 25 description and it will also be understood that while the disclosure herein is limited, in the main, to what I now consider the preferred form of the tool, various changes, both as to the general form and detail 30 structural features, may be made within the scope of the present invention.

Having thus described my invention, what I claim is:

1. A dental tool comprising a shank extended to form two normally separated 35 spring fingers terminating in suitably shaped members adapted when combined to form a containing receptacle for filling material and an ejector cooperating with the receptacle.

2. A dental tool comprising a shank, 40 extensions from the shank in the form of normally separated spring fingers terminating in suitably shaped members adapted when combined to form a containing receptacle for filling material, the said fingers being 45 provided at a point intermediate their length with a flexible resilient portion, and a rigidly supported ejector coacting with the flexible portion of the fingers to discharge the material from the receptacle. 50

3. A dental tool comprising a shank, extensions from the shank in the form of normally separated spring fingers terminating in suitably shaped members adapted when combined to form a containing receptacle 55 for filling material, the said fingers being reduced at a point intermediate their length to form a flexible resilient section, and a rigid ejector supported from a point on the tool in the rear of said flexible resilient section 60 of the fingers and adapted to coact with the receptacle.

GEORGE B. HAKINS.
